UNITED STATES PATENT OFFICE.

FRANK MERWIN WAKEMAN, OF DURHAM, MAINE.

DESIGN FOR A CORNET OR SIMILAR ARTICLE.

Application filed February 28, 1924. Serial No. 8,771. Term of patent 7 years.

To all whom it may concern:

Be it known that I, FRANK MERWIN WAKEMAN, a citizen of the United States, residing at Durham, in the county of Androscoggin and State of Maine, have invented a new, original, and ornamental Design for Cornet or Similar Article, of which the following is a specification, reference being had to the accompanying drawing, forming part thereof.

The figure is a plan view of a cornet or similar article, showing my new design.

I claim:

The ornamental design for a cornet or similar article, as shown.

FRANK MERWIN WAKEMAN.
